UNITED STATES PATENT OFFICE.

FRANKLIN A. NORCROSS, OF LORAIN, OHIO.

FOG-SIGNAL.

SPECIFICATION forming part of Letters Patent No. 361,776, dated April 26, 1887.

Application filed January 29, 1887. Serial No. 225,924. (No model.)

To all whom it may concern:

Be it known that I, FRANKLIN A. NORCROSS, of the town of Lorain, in the county of Lorain and State of Ohio, have invented certain new 5 and useful Improvements in Steam Fog-Signals, of which the following is a specification.

This invention relates to signals to be used by steam or sailing vessels in foggy weather; and it consists of a steam-whistle device of a 10 peculiar construction connected with an independent operating mechanism, whereby an automatic instrument is provided for uttering the signal sounds at stated intervals.

My signaling mechanism is constructed, combined, and arranged to operate substantially as hereinafter fully described, and pointed out in the claims.

In the accompanying drawings, Figure 1 is a perspective view of my improved signaling 20 device. Fig. 2 is a top or plan view of the same. Fig. 3 is a sectional view of the valve mechanism; and Fig. 4 is a face view of valve-seat, showing the holes which lead into the whistle-pipe and the mechanism closing one or two of 25 said holes.

A represents a base or bed plate, which supports all the working parts. At one end of 30 said bed-plate is placed a pillow-block, B, having journal-box supporting one end of a shaft, C, and on said shaft is provided a worm-gear pinion, D, and beneath said pinion is a counter-shaft, E, having a worm operating said pinion. Said shaft E is supported in bearings ee, fixed in a part of the said pillow-block B.

35 F is an oscillating engine supported upon the bed-plate A, and is connected with the crank-disk f on the shaft E, and comprises the motive power for giving motion to the said shafts, steam being applied by means of pipe I from any steam-generator.

G is a chambered disk having flanges gg, by which it is secured to the bed-plate by bolts, or otherwise. To its central part is provided a bearing for the shaft C, having a stuffing-box, 45 c, for making a tight joint. To the end of shaft C is attached a rotating disk, H, fitted to closely fill the chamber of the disk G, and to rotate therein, and said rotating disk H is inclosed steam-tight within the said chamber by a cap, 50 K, screwed or bolted onto said disk G. The face of disk H toward the cover or cap K has

an annular groove, h, forming a steam-space, into which steam is led by a pipe, J, fixed in the cap, as shown. To the disk G is also made a boss or projection, M, having a chamber, into 55 which three or any suitable number of holes, m m m, through the back wall of the chamber, lead, and from the said boss or projection arises a pipe, P, to which is connected a signal consisting of a steam-whistle, O. Through the 60 rotating disk H is made a hole, h', connected with the aforesaid steam-groove h, and also in such location that said hole h' will register with the holes m m m as said disk revolves, thereby intermittently opening and closing communication between said steam-chamber h and the chamber in boss or projection M, the purpose of which is to cause rapid successive sounds of 65 the whistle at stated intervals as the said disk H revolves.

A device for shutting off one or more of the holes m m m, consisting of a pin or spindle, N, is set in a transverse bore in the back wall of disk G, said pin projecting outward and provided with a stuffing-box, to prevent leakage. 70 The outer end of the pin is connected by joint with a hand-lever, R, by which it may be moved in or out, the inner end being intended to stop one or more of the said holes m, whereby the number of successive sounds of the whistle 75 may be governed.

Having described my invention, what I claim, and desire to secure by Letters Patent, is—

1. The combination, substantially as described, of a chambered disk inclosed with a cap supported on a suitable bed-plate, and having a central packed bearing for one end of a shaft carrying a rotating disk rotating within said chambered disk, and provided with a 85 steam-passage to intermittently open communication between an annular chamber or groove in the face of said rotary disk, and ports in the back wall of the chambered disk leading to the whistle-pipe during the revolutions of said 90 rotating disk.

2. The combination, substantially as described, of a chambered disk inclosed with a cap and supported on a suitable bed-plate or foundation, and having a central packed bearing for one end of a shaft carrying a rotating disk rotating within said chambered disk, and

provided with a steam-passage through it communicating between an annular chamber or groove in the face of said rotating disk, and ports in the back wall of said chambered disk, leading to the whistle-pipe, the shaft being propelled by means of worm-gear connected with and operated by an engine, substantially in the manner and for the purpose specified.

3. The combination, substantially as described, of a chambered disk inclosed with a cap supported on a suitable bed-plate, and having a central packed bearing for one end of a shaft carrying a rotating disk, and provided with a steam-passage through it communicat-

ing with an annular chamber or groove in the 15 face of said rotating disk, and ports in the back wall of said chambered disk leading to the whistle-pipe, and a pin or spindle working in a counterbore for controlling said ports, the shaft being propelled by means of a worm-gear 20 connected with and operated by an engine, substantially in the manner and for the purpose specified.

FRANKLIN A. NORCROSS.
